(57) CLAIM

The ornamental design for a multiple use spatula tool head, as shown and described.

DESCRIPTION

FIG. 1 is a side, top perspective view of the multiple use spatula head showing our new design, the broken lines showing the attached neck and handle portion are for illustrative purposes only and form no part of the claimed design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.
